United States Patent Office

Des. 231,920
Patented June 25, 1974

231,920

APARTMENT BUILDING

Charles J. Thomas, 8083 Forest Lake Drive,
Youngstown, Ohio 44512

Filed Oct. 30, 1972, Ser. No. 302,566

Term of patent 14 years

Int. Cl. D25—03

U.S. Cl. D13—1 A

FIG. 1

Des 231,920

FIG. 1 is a front elevation of the apartment building
FIG. 2 is a side elevation of the apartment building and
FIG. 3 is a side elevation showing the opposite side of the apartment building. The rear elevation is a mirror

I claim:

The ornamental design for an apartment building, as shown and described.
